YARN GUIDE

Peter J. Schoenster, Teaneck, N. J., assignor to
 Alfred Hofmann & Co., West New York, N. J.,
 a corporation

Application November 30, 1950, Serial No. 198,298

6 Claims. (Cl. 66—86)

1

This invention relates to yarn guides for flat knitting machines.

It has been proposed to provide for use in flat knitting machines, warp yarn guides having a yarn delivery end and yarn receiving end remotely located from the delivery end. In such guides, the channels extending from the opposite ends thereof, are closed at the receiving ends in order to prevent the yarns from leaving the channels during certain phases of the knitting cycles where the guide bars on which the yarn guides are mounted, move outwardly as a part of their to and fro movement. Thus, the yarns are threaded into the channels and are restrained against outward movement therefrom by means of longitudinally extending wires or rods located at the receiving ends of the channels.

Such known yarn guides entail technical difficulties in their fabrication, their attachment to the guide bars of the knitting machines and in the utility thereof.

Accordingly, an object of this invention is to provide improved yarn guides for flat knitting machines, which by reason of their structure and location of elements thereof, provide a simplified construction having distinct advantages in use.

Another object of this invention is to provide yarn guide means of the character described, for attachment to the movable guide bars of a flat knitting machine, which includes means for aligning a plurality of yarns in side by side relation with means for delivering the yarns to knitting elements of the machine, the aligning means taking the form of outwardly open channels which are so located relative to the yarn delivery means as to retain the yarns in their respective channels in any position of the guide bars.

A further object of this invention is to provide improved yarn guide means which includes a block having a plurality of elements in closely spaced, parallel relation, each element being formed with yarn delivery means at one end thereof and a plurality of closely spaced, parallel projecting means forming successive open yarn receiving and guiding channels, each channel being aligned with a yarn delivery portion, the spacing between each channel and its delivery portion being such that a yarn disposed in such channel and extending to the delivery portion, will remain in the channel irrespective of the amount of displacement between the yarn and the channel during various motions of the knitting cycles.

Still another object of this invention is to provide improved yarn guide means which in-

2

cludes a block mounted on a guide bar and having a plurality of closely spaced elements mounted therein in parallel relation, each element including a yarn delivery portion and a projection spaced therefrom, successive pairs of projections forming open yarn receiving means for aligning the yarns with respective yarn delivery portions, the spacing between the projections and the delivery portions being such that yarns will remain within the yarn receiving means in any position of the guide bar.

Other objects of this invention will in part be obvious and in part hereinafter pointed out.

The invention accordingly consists in the combinations of elements and arrangement of parts which will be exemplified in the constructions hereinafter described, and of which the scope of the invention will be indicated in the following claims.

In the drawing:

Fig. 1 is a partial side elevational view of a warp yarn guide embodying the invention, mounted on a guide bar;

Fig. 2 is a sectional view taken on the line 2—2 of Fig. 1;

Fig. 3 is a sectional view taken on the line 3—3 of Fig. 2;

Fig. 4 is a side elevational view of an element of the guide means shown in Fig. 1;

Fig. 5 is a perspective view of a modified form of the guide means embodying the invention; and

Fig. 6 is a side elevational view of a modified form of element which may be used in lieu of elements shown in Figs. 1 and 5.

Referring in detail to the drawing, and particularly to Fig. 1, 10 designates a yarn guide bar which is attached to a guide bar holder, not shown, of a flat knitting machine. Mounted along the longitudinal extent of bar 10 in side by side relation, are a plurality of similar yarn guide units 11, embodying the invention. Each guide unit 11 comprises a substantially rectangular block 12 of cast metal alloy having a flat outer face 13, a lower horizontal edge 14 and an opening 15 at the upper portion thereof, for receiving a screw 16 which secures the block to the bar 10.

Mounted in each block 12 are a plurality of similar metal elements 17, which are arranged in closely spaced, parallel relation. Each element 17, which may be formed of metal wire stock, is flattened and formed at its lower end with a yarn delivery eye 18. The shank 19 of the element 17 is bent intermediate the ends thereof to form a narrow doubled projection or hump 20. Such projection extends substantially at right angles

to the axis of shank 19 and provides a yarn aligning element, as hereinafter described.

The elements 17 may be suitably spaced and embedded in the block 12 as the same is cast, so that the lower ends of shanks 19 extend downwardly from the block edge 14 and the eyes 18 thereof are horizontally aligned. The upper ends of shanks 19 are so disposed within the block 12 as to have the projections 20 located immediately below the block edge 14 and extending outwardly of the block face 13. The projections 20 are in horizontal alignment with each other.

It will be apparent that each successive pair of projections 20 form an outwardly open channel adapted to receive therein a portion of a single yarn Y, the upper portion of which is supplied from a warp, not shown. The lower portion Y' of each yarn is threaded through an eye 18 of a corresponding element 17. Thus, the yarn portion Y' is directly aligned with eye 18 from the projection 20 and is retained in such alignment at all times. The aligned yarn portions Y' are delivered from the eyes 18 to the knitting elements of the machine with which guide bar 10 is associated.

The guide bar 10 is adapted to be moved longitudinally of the machine, as well as in transverse directions. Such movements are dictated by the knitting pattern during various motions of the knitting cycles, in a manner well known in the art.

It will be apparent from a consideration of Fig. 1, that the yarn portions Y' will maintain their alignment with their respective yarn delivering eyes 18 within the critical area required for the accurate manipulation of the yarns during the knitting cycles. The projections 20 will maintain such yarn alignment in any of the longitudinal positions of the guide bar 10, wherein the yarns Y may have an inclination to the left or the right, above projections 20, as indicated in the figure. The spacing between successive projections 20 is such as to form yarn guide channels slightly greater than the diameter of the yarn disposed therein.

It is also understood that the yarn portions Y' retain their aligned positions within the guide channels, when the guide bar 10 is actuated to cause the same to have a transverse or to and fro movement. In the case of movement of the bar to the left, looking at Fig. 2, the yarns will approach the guide bar and stay within the guide channels. When the guide bar moves to the right, looking at Fig. 2, the yarns will show a progressive increase in displacement relative to the guide bar, in successive portions thereof located at successively greater distances from eye 18. However, such displacement is relatively small at the lower portions of the yarns. Thus, the projections 20 are located at points spaced from the eyes 18 where the yarn displacement is less than the outward extent of the projections. By locating the projections 20 adjacent the eyes 18, as at the block edge 14, the projections may be relatively short.

With open channel yarn receiving means as defined by the projections 20, yarns Y may be quickly drawn from their warps, disposed within the receiving means and threaded through the delivery means at eyes 18, in a very short time.

Despite the complexity of the various movements of the guide bar 10 during the knitting cycles in accordance with the knitting pattern, the feeding movement of the individual yarns Y

to the knitting elements will be such as to eliminate fabric defects such as pinholes or the like, which are caused by excessive angular shift of the yarns in a critical area at their delivery points.

As shown in Fig. 5, elements 17', also formed from flattened wire stock, may include eyes 18' at the lower ends of shank portions 19' and single projections 20' bent from the upper ends at right angles thereto. The elements 17' are spaced and embedded in block 12 with the shank portions 19' extending downwardly from block edge 14. The projections 20' extend outwardly of block face 13 and are located slightly above edge 14. The projections 20' must have a length in accordance with their spacing from eyes 18' to allow the yarn portions Y' to remain within the channels formed by the projections when the bar 10 is moved to the right, looking at Fig. 2.

As shown in Fig. 6, shanks 19a formed with eyes 18 at their lower ends may be separate from projections 20a. Each set 17a of shanks and projections must be suitably related and spaced for embedding in block 12, to form successive open channels which are aligned with successive yarn delivering eyes. Here, also, the spacing between each eye 18a and its projection 20a must be such that the yarns will stay within the yarn receiving channels upon movement of the guide bar 10 to the right, looking at Fig. 2. Furthermore, each projection 20a may be so positioned as to be in slightly offset relation to an eye 18, thereby allowing the projections to be located in closer relation to the yarn delivering eyes 18.

It will thus be seen that there is provided yarn guide means in which the several objects of the invention are attained and which is well adapted to meet conditions of practical use.

As various possible embodiments might be made of the above described invention, and as various changes might be made in the embodiments above set forth, it is to be understood that all matter herein set forth or shown in the accompanying drawing, is to be interpreted as illustrative and not in a limiting sense.

Having thus described my invention, I claim as new and desire to protect by Letters Patent:

1. A yarn guide for attachment to the movable guide bar of a flat knitting machine, comprising a member adapted to be mounted on said guide bar, means including a plurality of closely spaced, elongated parallel members extending downwardly from the lower edge of said member for delivering a plurality of yarns in side by side relation to the knitting elements of said machine, and means on each of said elongated members including narrow projection extending outwardly of said first mentioned member to form a plurality of outwardly open channels, said channels being spaced from the lower ends of said downwardly extending members and located adjacent the lower edge of said first mentioned member whereby yarns disposed in said channels and extending to the lower ends of said downwardly extending members, will stay within said channels upon movement of said guide bar in any direction.

2. A yarn guide for attachment to the movable guide bar of a flat knitting machine, comprising a member having a flat outer face and adapted to be mounted on said guide bar, a plurality of similar elements mounted closely spaced, parallel relation on said member, each of said elements including an elongated portion extending below the lower edge of said member and

being formed with a yarn receiving opening at the lower end thereof and a narrow portion projecting forwardly of and at right angles to the outer face of said member, said projecting portions being located adjacent the lower edge of said member and forming a plurality of outwardly open guide channels.

3. A yarn guide for attachment to the guide bar of a flat knitting machine comprising a supporting member, a plurality of similar wire elements mounted on said member in closely spaced, parallel relation, each of said elements comprising a shank portion formed with an eye at one end thereof and including a guide forming portion extending substantially at right angles to the axis of said shank portion, said guide forming portion being located adjacent the lower edge of said supporting member.

4. A yarn guide as in claim 3, wherein said guide forming portion is disposed at the other end of said shank portion.

5. A yarn guide as in claim 3, wherein said guide forming portion is disposed intermediate the opposite ends of said shank portion.

6. A yarn guide for attachment to the guide bar of a flat knitting machine, comprising a member, a plurality of similar elements mounted on

said member in closely spaced, parallel relation, each of said elements being formed of an integral elongated member having an eye at one end thereof and bent intermediate the ends thereof to form an outwardly projecting guide forming means extending substantially at right angles to the axis of said elongated member, said elements being disposed with the eyes thereof extending below the lower edge of said first mentioned member and with the guide forming means thereof disposed adjacent the lower edge of said first mentioned member.
